Primary Examiner — Robert M Spear*Assistant Examiner* — Eliza Bennett-Hattan(74) *Attorney, Agent, or Firm* — Buchanan Ingersoll & Rooney PC(57) **CLAIM**

The ornamental design for a spring motor housing for a window covering, as shown and described.

DESCRIPTION

FIG. 1 is perspective view of the spring motor housing for a window covering;

FIG. 2 is a front view thereof;

FIG. 3 is a rear view thereof;

FIG. 4 is a top view thereof;

FIG. 5 is a bottom view thereof; and,

FIG. 6 is a left side view thereof. The right side view thereof is a mirror image of the left side view.

The elements shown in broken lines in the drawing depict environmental subject matter only and form no part of the claimed design.
